FIG:2

FIG: 3

FIG: 4

The diagram illustrates the circuit for the Answer back Receptor (A). It features a complex network of relays and contacts. Key components include:

- Starter:** Located at the bottom left, connected to terminal 19.
- Receiving Distributor:** Located at the bottom left, connected to terminal 1.
- Relay 33:** Located in the upper left, connected to terminal 32.
- Relay 12:** Located in the center left, connected to terminal 7.
- Relay 6:** Located in the center left, connected to terminal 5.
- Relay 20:** Located in the center left, connected to terminal 19.
- Relay 35:** Located in the center right, connected to terminal 14.
- Relay 15:** Located in the center right, connected to terminal 15.
- Relay 73:** Located in the center right, connected to terminal 11.
- Relay 17:** Located in the center right, connected to terminal 17.
- Relay 23:** Located in the center right, connected to terminal 23.
- Relay 21:** Located in the bottom right, connected to terminal 25.
- Relay 16:** Located in the center right, connected to terminal 16.
- Interference Relay 34:** Located in the upper right, connected to terminal 34.
- Interference Relays 13 and 18:** Located in the center right, connected to terminals 13 and 18 respectively.
- Storing Device:** A label indicating a component between relay 12 and relay 35.
- Receiving Printer:** A label indicating a component between relay 15 and relay 17.

The connections are as follows:

- Relay 33 is connected to terminal 32.
- Relay 33 is connected to the coil of relay 35.
- Relay 35 is connected to terminal 14.
- Relay 12 is connected to terminal 7.
- Relay 12 is connected to the coil of relay 35.
- Relay 12 is connected to the coil of relay 15.
- Relay 15 is connected to terminal 15.
- Relay 73 is connected to terminal 11.
- Relay 73 is connected to the coil of relay 17.
- Relay 17 is connected to terminal 17.
- Relay 6 is connected to terminal 5.
- Relay 6 is connected to the coil of relay 15.
- Relay 20 is connected to terminal 19.
- Relay 20 is connected to the coil of relay 15.
- Relay 20 is connected to the coil of relay 23.
- Relay 23 is connected to terminal 23.
- Relay 23 is connected to the coil of relay 21.
- Relay 21 is connected to terminal 25.
- Relay 21 is connected to the coil of relay 16.
- Relay 16 is connected to terminal 16.
- Relay 16 is connected to the coil of relay 17.
- Relay 17 is connected to terminal 13.
- Relay 17 is connected to the coil of relay 18.
- Relay 18 is connected to terminal 18.

3 Claims. (Cl. 178—69)

In operating with a type-printing telegraph system on a connection in which interference may occur, for example a radio connection, a disadvantage, as compared with systems in which the actual signal is recorded, is that a wrong signal cannot be recognized as such. In systems in which the actual signal is recorded it is occasionally possible for a skilled telegrapher to recognize wrong signals.

10 The object of the invention is to provide a type printing telegraph system in which the unnoticed reproduction of signals or signal elements wrongly received may be avoided.

This object is attained by the fact that the 15 signals are transmitted by means of double current—that is to say the working elements of the signals are transmitted by means of working or marking current and the resting elements by means of resting or spacing current. Furthermore, in the receiving circuit an error-detecting 20 device is provided whereby the presence of disturbing impulses or the dropping out of signal elements is made recognizable.

The construction of the printing telegraph 25 system so as to achieve the object of the invention results in a marked increase in traffic transmission capacity.

According to the invention, the desired effect 30 may be attained by the provision of a device having means causing the working and resting signal elements, respectively, to close and open a local circuit directly or indirectly operating the printer, and causing disturbances (either fading or additional current impulses due to atmos- 35 pherics) to close said local circuit and to close an indicating circuit which renders the disturbed signals recognizable.

The invention may be employed in all known 40 type printing telegraph systems. It has particu- 45 lar advantages in two-way communication between two stations, and in systems in which, for the purpose of eliminating interference, each signal element is sent out several times by the transmitting device and is received as many times by the receiving device. These advantages will be explained more fully hereinafter.

The invention will be explained with reference 50 to the accompanying drawings showing several constructional examples. In these drawings:

Figure 1 shows an error-detecting device constructed according to the invention.

Figures 2 and 3 relate to modifications of the error-detecting device.

55 Figure 4 shows printing telegraph system ac-

cording to the invention, employed for two-way communication between two stations.

Figures 5—9 relate to three constructional examples for systems in which the signals or signal elements are transmitted and received a plurality 5 of times.

In Figure 1, the error-detecting device comprises two relays, one of which is acted upon by the working (marking) current and the other by the resting (spacing) current of the transmitter. 10 The tongues of these relays co-operate in such a manner that when the reception is not disturbed so that one tongue rests in the working position and the other in the resting position, the received signal elements are passed on to the printer portion 15 of the receiving apparatus.

If, however, the reception is disturbed either by a "positive" disturbance producing an additional current impulse or by a "negative" disturbance causing a working or resting signal current impulse to be annulled, the tongues both lie 20 in the working position, or both in the resting position. Although the mutilated signals are passed on, they are, nevertheless, designated as 25 erroneous by means of an additional circuit which is rendered operative in response to the occurrence of the interference. It is also possible to prevent the actuation of the printing apparatus 30 in response to mutilated signals. Instead of this, 35 it is also possible to keep the disturbed signals away from the receiving apparatus.

At the transmitting end double current is employed. In the case of a radio connection for 40 example, a so-called double wave transmitter or 45 two signal frequencies are employed, which are modulated on a common carrier wave. In any case, the working signal elements are transmitted with working current and the resting signal elements are transmitted with the resting current.

The two sources of current, which produce the 50 working current and the resting current, are shown at 1 and 2, and 3 is the tongue of the transmitting relay. This circuit arrangement of the transmitting station is not essential for the 55 invention.

At the receiving end, both signal currents are received, and are thereupon separated from one another by known means such as filters 4, 5. The resting current and the working current are 50 now fed to rectifiers 6 and 7 respectively and these rectifiers act upon relays 8 and 9 respectively. The tongues of these relays are applied against the resting contact *r* when the corresponding rectifier does not receive any signal voltage, and 55

against the working contact *w* when the rectifier receives signal voltage.

Due to the double wave transmission, both relay tongues occupy opposite positions when there is no disturbance in the reception. When the tongue of the relay 8 occupies the working position (*w*), the tongue of the relay 9 occupies the resting position (*r*) and vice versa.

If, however, the received signal element is disturbed, either on account of the occurrence of an additional current impulse or due to the absence of a transmitted current impulse, both relay tongues are shifted to corresponding positions, that is, both working or both resting. The cause may be a fading condition or any atmospheric disturbance.

The tongues of the relays 8 and 9 are electrically connected together and are also connected by a lead 10 to the printer apparatus. The resting contact of the relay 8 and the working contact of the relay 9 are connected together and to an interference relay 11, while the working contact of the relay 8 and the resting contact of the relay 9 are both connected to a source of current 12. One side of the relay 11 and one side of the source of current 12 are grounded.

With this connection, the interference relay 11 receives current when the tongues of both relays 8 and 9 occupy the resting position *r* (interference through fading) or when they both occupy the working position *w*, (interference through an additional current impulse). In the event of undisturbed reception, on the other hand, the relay 11 does not receive any current.

35 The printing apparatus connected to the lead 10 receives working current when the relay 8 is in the working position and the relay 9 is in the resting position. It does not receive any current when the relay 8 is in the resting position, 40 and the relay 9 is in the working position, and it receives working current when both relays occupy the same position (that is to say in the case of interference). In the last case, however, the received signal may be indicated as an error 45 by means of the interference relay 11, or in any other manner. This relay, therefore, indicates erroneous signals with absolute certainty.

It is obvious that the interference relay 11 may act upon the printer in many different ways. 50 Thus, for example, a blank or another interference signal, such as a special printed sign, may be given. Furthermore, the starting of the printer may be prevented in systems in which the code signal is followed by a locally initiated 55 printer-actuating impulse. The practical execution depends upon the particular telegraph apparatus employed, and is not an essential feature of the invention.

According to a modification of the invention 60 the occurrence of a wrong signal element may be rendered recognizable by the employment of means responsive to such an erroneous signal for intercepting the working or resting current as supplied to the printer. The printer will then 65 function as when "spacing" instead of printing erroneous characters. This feature is of considerable importance when using uniform length code signals in printing telegraph systems, as will be shown more clearly hereinafter.

70 Fig. 2 illustrates how the relays 8 and 9 may be so employed that the disturbed signal element is kept away from the printer. As will be seen from this figure, the printer does not receive any current when the tongues of the relays 8 and 9 are both in the resting position or both

in the working position, because the current sources 12 and 13 will be connected together. If, on the other hand, the received signal is undisturbed, the telegraph apparatus receives either working current or resting current from the current sources 12 and 13, respectively.

Figure 3 shows another constructional form. In the event of interference-free reception, the anode current of one of the rectifiers 6 or 7 flows through one of the two windings of the relay 98, so that the tongue of the relay rests against one of the two contacts. In the event of interference, current either flows through the two coils in opposite directions or alternatively the two coils are dead. In both cases the tongue of the relay which always returns to the middle position, remains in this middle position, so that the telegraph apparatus does not receive any current.

The invention as used in two-way communication renders it possible to repeat the transmission of a certain signal by one of two stations, if this signal is not correctly received at the other station. If, therefore, a signal is mutilated during transmission, it is repeated and if it is not mutilated it will not be repeated.

According to the invention, this method is preferably carried out in such a manner that the reception of a mutilated signal results automatically in a warning signal being sent back, 30 whereby the signal is repeated in the transmitting station, while the reception of an interference-free signal results automatically in a monitoring signal being sent back, whereby the succeeding signals of a message are transmitted 35 in regular course.

Figure 4 will serve for explanation of the foregoing. In this figure, a constructional form of the system according to the invention is shown diagrammatically by way of example, it being assumed that each transmitted signal consists of 40 five elements (5-unit code). The two-way or cross traffic takes place between two stations A and B, which are substantially constructed in the same way. For the sake of simplicity, only station A has been shown in the drawings. Each station has on the left hand side a receiving device and on the right hand side a transmitting device. The parts of the individual station are denoted by numbers, and will be distinguished 45 from one another by the addition of the letter A or B. Thus, for example, A15 is the receiving apparatus of station A and B15 the receiving apparatus of station B.

The vertical strokes under the number 1 represent the moments at which a distributor (or any other equivalent device) connects the receiving device of each station with the transmitter, say, through a radio communication channel, the vertical strokes under the number 2 represent the moments at which another distributor connects the transmitting device with the channel of communication. The individual moments of each vertical series follow one another in the direction of the arrows shown on the drawings.

The transmitting distributor A2 of station A runs synchronously with the receiving distributor B1 of station B, and the transmitting distributor B2 of station B runs synchronously with the receiving distributor A1 of station A. Both distributors in each station may be coupled together mechanically. It is immaterial whether synchronism is obtained by means of distributors moving continuously or discontinuously. In 70 75

the present instance an installation with continuously rotating distributors has been assumed. It is further assumed that the station B is transmitting a message to station A. The correction current impulses for maintaining synchronism of the distributors in the transmitting station and the receiving station are sent out by the transmitting station B through distributor segments B3 and B4, and are received by the receiving station A on segment A5. The correction magnet of station A is connected to a protective device A6. The latter operates in the manner already described in the foregoing and may be so constructed, for example, that if an interference occurs while the receiving distributor brush is traversing segment A5, the correction magnet of station A will not operate. Premature correction is, therefore, avoided.

The five elements of each signal are transmitted by station B on segments B26 to B30, and are received by A on segments A7 to A11 whence they are transferred to the protective and signal storing device A12. The protective device serves to ascertain whether one or more of the five signal elements received has been disturbed. If none of the five elements is disturbed, the interference relay A13 remains unenergized, and the actual telegraph recording apparatus A15 receives a starting current impulse by way of the resting contact A14 of the relay A13 and a contact of the distributor A1, which latter contact is not shown. The telegraph apparatus A15 then becomes operative, receiving the signal elements stored up in A12 and converting them into printing or recording or interpreting them in any other manner. Furthermore, a positive (spacing) current impulse is sent through segment A18 to station B by way of the tongue A16 of the polarized relay A17 and is received by B on segment B19. This current impulse is received by a device B20, which is also constructed as a protective device. An interference relay B21 is connected to this device. If the spacing current impulse transmitted by A is received undisturbed, the interference relay B21 is not energized, and consequently the transmitting apparatus B22 receives a starting current impulse by way of a contact (not shown) of the corresponding distributor from the protective device B20 by way of the resting contact B23 of the interference relay B21. The transmitting apparatus B22 is thereby rendered operative. The spacing contacts of the five transmitting tongues of this apparatus are connected at B24 to the positive terminal of a source of current, and the marking contacts of the tongues are connected through the spacing contact of the interference relay B21 to the negative terminal of a source of current. By the starting of the transmitting apparatus, the transmitting tongues are connected to voltages which correspond to the next signal, so that this signal is now transmitted at the moments B26 to B30. In the station A, this signal is again received at the moments A7 to A11. The process described in the foregoing is thus repeated and the second signal is also printed and so on.

If, in transmitting the first signal one or more elements of this signal are received disturbed in the station A at the moments A7 to A11, the interference relay A13 is energized.

This relay, like the interference relays 21 and 35, on being energized remains in the energized condition for one complete revolution of the distributor. At the end of this revolution it is either

de-energized or re-energized according to whether the current impulses received at this moment are undisturbed or disturbed.

When the relay A13 is energized the contact A14 is broken, so that the receiving apparatus A15 does not receive any starting current impulse, and consequently does not record any signal. At the same time, through the energizing of the relay A23, the relay A17 is given a negative current impulse (working current impulse) is transmitted from the station A to the station B on segment A18 by way of the tongue A16 of the said relay A17.

This marking current impulse is received on segment B19 by the protective device B20 and the result is that the starting circuit is interrupted. Hence the transmitting apparatus B22 does not receive any starting current impulse, and hence cannot send out any fresh signal, but instead the previous signal is repeated. This is necessary, because no signal was printed on the first reception in the station A.

It follows from the foregoing that in the event of disturbed reception, the receiving station asks the transmitting station, by means of a warning signal, to repeat the signal which has already once been transmitted.

As described in the foregoing, this request is received at the station B on segment B19, there being a possibility that, due to an interference, the warning signal transmitted by station A is not received correctly at station B. Since then it is not possible to ascertain whether a repeat has been requested or not, in this case for the sake of certainty no fresh signal is transmitted and also the old signal is not repeated. This may be effected for example, as follows:

If an interference is received at the moment B19, the interference relay B21 is energized. The starting circuit of the transmitting apparatus B22 is interrupted at B23. The tongue B25 of the interference relay B21 connects the positive terminal of a source of current to the working contacts of the five transmitting tongues, so that on segments B26 to B30, five spacing current impulses are transmitted. The receiving apparatus of station A does not respond to these five spacing impulses, since the latter correspond to the resting condition of the transmitter.

The receiving device of station A, however, must ascertain whether the station B at segment B19 has or has not reacted to the last positive or negative warning current impulse transmitted by A, because only in this case is the station A in a position to request, if necessary, the repetition of the last signal or the transmission of the next signal.

Station A could ascertain the disturbed reception of the warning impulse by the fact that five spacing impulses are received from the station B. In view of the possibility that these impulses may be disturbed, it is preferable to transmit a special signal from station B, in addition to the five spacing impulses. This signal is preferably transmitted on segment 31 and preceding the five spacing impulses. Normally, that is to say, if the warning signal is received correctly by B20, the special signal consists of a negative current impulse (working current impulse), which is transmitted by way of the resting contact of the tongue B25. In station A, this signal is received through segment A32 by a protective device A33 which shows in known manner whether the signal received consists of a resting cur-

rent impulse, a working current impulse, or an interference.

By the reception by A33 of a (negative) working current impulse or an interference, the circuit of the relay A17 is connected to earth by a contact (not shown) of the distributor by way of a contact (likewise not shown) within the device A33, and through the resting contact A34 of the relay A35. The contact within the device A33 5 interrupts the circuit, however, if the special signal consists of a (positive) resting current impulse. Furthermore the circuit is likewise broken, if the relay A35 is energized, which only takes place in the event of undisturbed reception of the 10 five resting units by the device A12.

By the use of this circuit, the relay A17 can never be influenced by the fact that the signal received by A12 is or is not disturbed, if the special 15 signal received by A33 consists of a positive or resting current impulse. In this case, the circuit of the relay A17 is already interrupted within the device A33 itself so that the tongue A16 remains in the position which it had attained after reception 20 of the previous signal.

25 The consequence of the reception of such a positive current impulse is that the station A at the moment A18 retransmits the same warning signal in the form of a resting or working current impulse by way of the tongue A16. If this 30 current impulse is now received in B by B20 undisturbed, the repetition of the previous signal or the transmission of a fresh signal can take place. On reception in A of a negative current impulse 35 or a disturbance, however, the signal to be received at the moments A7 to A11 is stored up and any disturbance of this signal is reported by the relay A18.

The probability of the warning signals and the other special signals being transmitted undisturbed 40 may, of course, be increased in different ways, for example, by multiple transmission of these signals, or by lengthening or shortening them. It is also possible, by such means, to reduce the possibility of interference of the five elements 45 of each signal. The time distribution of the above-mentioned contact moments shown in the figure, the proportion of their length and the number of these contact moments are therefore not essential. They may be varied without departing 50 from the principle of the invention.

It is obvious that a certain time is necessary in order to transmit by means of the transmitting apparatus of the receiving station a warning signal to the transmitting station. This signal can 55 only be transmitted when the five elements of the transmitted signal have been received and examined. Some time elapses, therefore, before the transmitting apparatus of the transmitting station can start again. The time of waiting between 60 the successive transmissions of the same or different signals may if necessary be filled in with the signals of another telegraph system which employs the same transmission channel. This 65 may be effected by means of contact members, which bring about in known manner a suitable time distribution, so that the individual telegraph systems can employ the transmission channel successively.

70 It is furthermore obvious that the connections as shown in Figure 4 may also be constructed otherwise within the scope of the invention. Thus, for example, the devices 6, 12, 20 and 33 75 are not confined to a definite form of construction. This already follows from the discussion

of the protective devices shown in Figures 1, 2 and 3. It is also not necessary to employ special interference relays 13, 21, 35. The circuits which are controlled by these relays may also be opened or closed by the protective devices themselves.

A further possible means of combating interference in a type printing telegraph system according to the invention resides in the application of the known principle namely, that interference may be eliminated up to a certain extent by repeated transmission and reception of all signal elements and signals.

The repeating systems known for this purpose are generally only capable of combating interference of a certain character, that is to say, either interference due to additional current impulses, or interference due to the absence of current impulses.

For telegraph systems in which both types of interference may occur (in the case of radio 20 telegraphy, for example, fading and atmospherics interference), so that resting signals and working signals may be incorrectly received, efforts have been made to discover means in order either to give the fading interference the character of atmospheric interference (that is to say, of additional current impulses) or to give the atmospheric interference the character of fading interference (that is to say of absent current impulses). The said means are provided in the receiving installation in front of the repeating system and the actual receiving apparatus, and result in the receiving apparatus being supplied incorrectly either with working signals only or with resting signals only. In such 30 systems, the repeated reception of the working current element or resting current element results in the formation of a working current signal or a resting current signal.

This property of the known systems immediately shows the great disadvantage of such systems, namely, that the repeated reception of working or resting current elements, which are not caused by a repeatedly transmitted signal but by interference, can lead to the formation of 45 a signal. This signal must then be wrong, however, and the mistake will not be noticed.

If, on the other hand, the principle of repetition is employed in combination with the present invention the undisturbed reception of a single 50 transmission is sufficient in order to render possible the reproduction of the correct signal in the actual receiving apparatus because each interference is indicated with absolute certainty. If none of the transmissions is received undisturbed this is also rendered recognizable with certainty 55 in the receiving apparatus. The unnoticed reproduction of a wrong signal is therefore impossible. Several constructional forms will be described hereinafter, by way of example, of a 60 testing device according to the invention, which is adapted to be provided in the receiving installation between the protective device and the actual receiving apparatus, and which renders it possible to ascertain whether, in the repeated transmission, at least one of the received signals is correct. If this is so, this signal is passed on further to the telegraph apparatus, so that the latter is set in operation. If, however, none of the signals passed on by the protective device is 65 undisturbed, an interference signal is supplied in any manner to the telegraph apparatus, or the operation of the said apparatus is prevented.

The testing device must satisfy the condition 70 of being able to ascertain and store the difference 75

between three different units which can be given by the protective device, that is to say, between a working signal, a resting signal, and an interference signal (or zero signal). Various means may be employed for this purpose, and the following are worthy of note:

5 1. Condensers which are adapted to receive and re-transmit subsequently the difference between a positive current impulse, a negative current impulse and no current impulse.

10 2. Relay circuits which are adapted to receive and re-transmit the difference between a positive current impulse, a negative current impulse and zero current impulse, or between current impulses 15 of different intensities, or between direct current and alternating current.

15 3. Relays in combination with mechanical devices for receiving, storing and retransmitting the three different units.

20 In Figure 5 is shown a testing device employing a distributor or any other equivalent device which is driven synchronously, in rhythm with the repeated transmission, with the repeating device of the transmitter, which supplies successively 25 to a condenser the quantities of electricity, given by the protective device during the repeated transmission of each signal and which subsequently employs the charge of this said condenser for actuating the receiving apparatus.

30 It has been assumed in the figure that each signal element is received three times and hence can be tested three times.

The current impulses which are given by a protective device, not shown (for example according to Figure 2) and which may comprise a positive current, a negative current or zero current in order to give a resting signal, a working signal, or an interference signal, are supplied to the lead 25. 21, 22 and 23 are contacts of a distributor (contact disc, contact drum, or the like), which are closed just at the moments at which the repeated signal elements are received in the lead 25. It depends upon the construction of the distributor whether the contacts 21, 22 and 23 are separated 40 from one another or are combined to form a single contact. The construction of the distributor is of course optional, the only condition being that it shall operate synchronously with the repeating system of the transmitter.

45 50 When the contact 21 is closed, the first current impulse given by the protective device has the opportunity of charging or not charging a condenser 26. The contact 22 does the same for the second current impulse and the contact 23 for the third current impulse. Since the three current impulses belong to the same signal element, the condenser 26 may be charged only in a certain direction either positively or negatively, or may remain uncharged. Current impulses of opposite 55 directions are not possible in the same signal element, since the protective device either passes on the received signal correctly or not at all, and a wrong transmission is impossible.

60 After the lapse of the third repetition, the condenser is hence charged certainly in the correct direction, if an undisturbed signal element has been received at least once by the protective device. If this is not the case, the condenser is not charged.

65 70 After the condenser has functioned to receive three times a correct current impulse the distributor closes the contact 24, whereby the condenser can discharge through a polarized relay 27 and a non-polarized relay 28. The tongue of the polarized relay 27 is applied to the resting

contact or the working contact, a resting or working current impulse being passed on to the telegraph apparatus by the energizing of the relay 28. If the condenser 26 has no charge, the non-polarized relay 28 is not energized. An interference signal can be then transmitted to the telegraph apparatus by the resting contact of this relay.

The non-polarized relay hence serves to distinguish current and zero current from one another, and the object of the polarized relay is to transfer the current direction (working or resting current) to the receiving apparatus. In other respects, it is clear that the circuit in which the condenser 26 is discharged may be constructed in different ways. This construction depends, for example, upon the nature of the telegraph apparatus connected thereto.

75 When, after the repeated transmission of a definite signal element, the condenser 26 has performed its action, it is in a position to receive the current impulses of a following signal element. The explanation given above has been limited to one signal element merely for the sake of simplicity, for example to the first signal element of a signal comprising five elements.

The manner in which the condenser, after exerting its effect can, if necessary, be completely discharged for the sake of security, and the manner, when the nature of the connected telegraph apparatus demands, in which the relay 28 can be maintained energized for some time, for example by means of a holding winding, and a special contact on the distributor, after the condenser has already been discharged, will now be explained.

80 Figure 6 shows diagrammatically the construction of another testing device in which a number of relay chains are employed. It has been assumed that each signal element is transmitted twice. The relay chains are closed one after the other by a distributor or an equivalent device, driven synchronously with the repeating device of the transmitting end, at moments in which the individual current impulses or zero current impulses, given by the protective device during the repeated transmission of the same signal element, arrive at the testing device. The relay chains are constructed in such a manner that testing of the received current impulses is carried out and the receiving apparatus is brought into action when at least one of the repeated transmissions is received undisturbed.

85 On the left hand of the figure is shown the protective device which in principle agrees with that shown in Figure 2. Between the tongues of the two relays of the protective device are situated a polarized relay and a non-polarized relay. With this circuit, as in Figure 2, on the reception of an undisturbed signal element, a resting current or a working current is sent into the lead 35, and on the reception of a disturbed signal element, no current occurs in the said lead.

90 The relay chains of the testing device each comprise a non-polarized relay 41 with a holding contact 36, and in series therewith a polarized relay 42. The contact 31 of the distributor is closed at the moment at which the protective device operates on the first reception of the twice transmitted signal element. If the reception is 70 undisturbed, the protective device gives rise to a working current or a resting current and the non-polarized relay is energized and is kept energized by means of its holding contact 36. The polarized relay 42 applies its tongue, in accordance 75

with the direction of the received current impulse, either to the resting contact or to the working contact, so that this current impulse is passed on by way of the contact 37 of the non-polarized relay 41 to the second relay chain, whereby this second relay chain which was originally connected to the lead 35 by the contact 38 is disconnected from the protective device.

At the moment of the reception of the second transmission, the contact 32 of the distributor is closed, the non-polarized relay 43 is then energized and is maintained energized by way of the contact 38, while, by means of the polarized relay 44, a current impulse is supplied to the telegraph apparatus. The contacts 33 and 34 of the distributor have the object of short-circuiting the holding winding of the relays 41 and 43 and of returning the circuit into the original state, after the respective relay chains have completed their action.

If an interference occurs in the first transmission of the signal element, the protective device does not transmit any current impulse. In this case, the non-polarized relay 41 is not energized, the result of which is that the second relay chain remains connected to the lead 35. On the second reception of the repeated signal element, the second relay chain then comes into action. If this reception is undisturbed, the relays 43 and 44 are energized, and the telegraph apparatus receives a corresponding current impulse. If, however, the second transmission also is disturbed, the non-polarized relay 43 is not energized and an interference signal is supplied to the telegraph apparatus by means of the contact 40 and a contact, not shown, on the distributor. If the contacts 31, 32, 33, 34 of the distributor are closed in known manner in the correct sequence, the first relay chain will be ready to receive a new current impulse, whilst the telegraph apparatus is still being fed by the second relay circuit.

Figure 7 shows a third construction of the testing device. This operates substantially in a mechanical manner.

At the transmitting end of the telegraph system, a perforated strip 57, on which the signals to be transmitted are fixed, is passed through three automatic transmitters 51, 52, 53 in succession. These transmitters are so connected to a distributor 59 that they are connected in succession to the transmission channel.

The perforated strip runs through the three transmitters and the elements of each signal are transmitted automatically three times. The time intervals between the successive transmissions are quite optional.

At the receiving end are three so-called reperforators 54, 55, 56. These are located behind a distributor 61, which follows the protective device 60 and is driven synchronously with the distributor 59 of the transmitting station. The receiving distributor connects the three reperforators to the transmission channel at the moments at which the current impulses originating from the transmitting station set the protective device 60 into operation.

A strip 58, the speed of which is equal to that of the perforated strip 57 of the transmitting station, is passed through the three reperforators.

A given signal is transmitted on the first reception to the reperforator 54 and this reperforator produces a perforation in the strip for each signal element or, if one or more of the signal elements are received disturbed, does not produce perforations for these elements.

In order that the reperforators can show the difference between the three different units (positive current impulse, negative current impulse and no current impulses), the perforations caused for example by a positive or resting current impulse are offset in the direction of the strip relatively to the perforations caused by a negative or working current impulse. The relative position is shown in Figure 8. This figure relates to the case in which each signal comprises five units. In the transverse direction of the strip there is room for five perforations. The perforations for the resting units are not situated, however, on the same transverse line as those on the working units. It has furthermore been assumed that the signal which should be received by the reperforator 54 consists of three resting units and two working units.

At the moment at which the repeatedly transmitted signal is received for the second time, the distributor switches in the second reperforator 55. At this moment, the strip 58 has been advanced until the perforations caused by 54 on the first reception are situated exactly opposite the perforating members of the reperforator 55. If now on the first reception, no perforation was produced at certain points of the strip 58, due to interference of one or more of the five signal elements, the reperforator 55 can correct this fault, unless an interference again occurs just at this moment. The same applies for the third reperforator 56, which comes into operation on the third reception of the transmitted signal.

This testing device also operates in such a manner that the receiving apparatus is set into operation when the protective device passes on at least once a signal (or signal element) which has not been mutilated by interference.

When, due to the occurrence of interference, none of the three reperforators is successful in producing a correct perforation, there is in the strip a non-perforated place which is shown in Figure 9 and which renders recognizable the wrong reception with absolute certainty.

After the strip has left the last reperforator 50 it is passed for example to an apparatus which converts the perforations to type printing. This type printing apparatus may be so constructed that in the absence of a perforation it produces an interference signal.

In addition to the provisions on the lines set forth in the foregoing, of a protective device and a testing device, the invention may also be employed in telegraph systems with repeated transmission of all signals, by combining a protective device with two known repeating systems, one for the working current and the other for the resting current.

What we claim is:—

1. In a telegraph system of the character described, a receiver for receiving working and resting current impulses, and a protective device associated with said receiver for protecting the receiver against unnoticed reproduction of false signal elements, said protecting device comprising means controlled by the received working current and other means controlled by the received resting current cooperating together to render the reception of disturbed signal elements recognizable in the receiver.

2. In a telegraph system of the character described, a receiver for receiving working and resting current impulses, and a protective device associated with said receiver for protecting the receiver against unnoticed reproduction of false

signal elements, said protecting device comprising two relays, the armatures of which are shiftable to working and resting positions, one of said relays being controlled by working current and the other being controlled by resting current, said relays being operable in the event of undisturbed reception so that the armature of one relay is in working position and the armature of the other in resting position, and so that in the 10 event of interference both relay armatures are in the same position, and means operable upon the armature of one relay being in the working position and that of the other relay being in the resting position for passing the signal elements 15 to the receiving apparatus and when both armatures are in the same position for rendering the interference recognizable.

3. In a telegraph system of the character described, a receiver for receiving working and rest-

ing current impulses, and a protective device associated with said receiver for protecting the receiver against unnoticed reproduction of false signal elements, said protecting device comprising a relay having two windings and an armature movable to working and resting positions, one of said windings being controlled by working current and the other winding being controlled by resting current, said windings being opposed so that in the event of undisturbed reception the armature is moved to either the working or resting position and in the event of interference the armature will be held in neutral position, and means operable upon the shifting of the armature to either the working or resting 10 position for passing the signals to the receiver. 15
